CONTROL MECHANISM FOR SHUTTLE
CHANGING LOOMS

William W. Robertson, Marlboro, Mass., assignor to Crompton & Knowles Loom Works, Worcester, Mass., a corporation of Massachusetts

Application August 5, 1935, Serial No. 34,660

10 Claims. (Cl. 139—231)

This application is a continuation in part of my copending application Serial No. 14,805 filed April 5, 1935 for a Shuttle changing loom.

This invention relates to improvements in shuttle changing looms and it is the general object of the invention to prevent the completion of a shuttle changing operation if the active depleted shuttle should fail to reach its shuttle box at the shuttle changing side of the loom.

10 In the type of loom to which my invention more particularly relates weft detecting mechanism is located on that side of the loom opposite the shuttle changing mechanism and acts upon substantial depletion of weft to initiate change in the shuttles. This change involves the stopping of the loom, the ejection of the depleted shuttle, the placing of a fresh reserve shuttle into active position, and restarting the loom. These several operations are accomplished by means of a so-called change shaft having cams which operate in proper sequence to perform the necessary operations. The loom is so controlled that it comes to rest during the replenishing period with the lay in back position. If the active shuttle should fail to be boxed on the magazine side the shuttle changing mechanism might, unless otherwise controlled, place a reserve shuttle into action so that the protector mechanism would be moved to running position to permit resumption of weaving, and a shuttle smash would result due to the fact that the depleted shuttle would still be in the shed. It is an important object of my present invention to prevent the shuttle changing mechanism from placing a reserve shuttle into the shuttle box when the active depleted shuttle fails to be correctly boxed.

40 In carrying a convenient embodiment of my invention into effect I provide a control hook to prevent complete rearward movement of the conveyor if the active shuttle fails to reach its shuttle box. The outgoing shuttle must be removed from the shuttle box before the conveyor can replace it with a fresh shuttle. In order that the interval between ejection and replacement may not interfere with the changing operation, I rely upon the protector finger to unlock the shuttle changer when the active shuttle reaches its box before ejection. This happens in sufficient time to permit a complete indication to be given before the shuttle changer can get beyond control of the lock.

45 It is a further object of my present invention to provide mechanism which sets the hook in stopping position before arrival of the shuttle

5 at the magazine end, the protector thereafter returning the hook to non-holding position by the boxing of the shuttle. In this way there is no time relation between the ejector and conveyor movements to interfere with the conveyor when conditions are proper for a shuttle change. The aforesaid results may be accomplished by control fingers set by the same devices which stop the loom for shuttle change.

10 When the active shuttle is picked from the detector side of the loom neither of its shuttle boxes will be occupied and the protector finger will therefore move temporarily to stopping position and I arrange the timing of the parts so that a control finger will be moved to controlling 15 or stopping position prior to arrival of the shuttle at the magazine end. If the shuttle fails to be boxed the control finger remains in position to keep the hook in conveyor restraining position, but if the shuttle is correctly boxed it acts 20 before its ejection can begin to move the controlling finger and therefore the hook out of arresting position.

25 The last operation of the shuttle changing period is to restart the loom and if shuttle change has been prevented as hereinbefore described I provide mechanism to prevent restarting, this mechanism preferably being actuated through the same hook which restrains the conveyor and by a force derived from the latter.

30 While I have shown the invention I have associated with a double shuttle loom employing two shuttles to be picked simultaneously for the weaving of a double fabric, yet I do not wish to be limited to such a loom, inasmuch as certain features of my invention operate independently of the number of shuttles which arrive at a given time on the shuttle changing side of the loom and the mechanism shown for either the upper or the lower shuttle box can be used for 40 a single shuttle loom.

35 With these and other objects in view which will appear as the description proceeds, my invention resides in the combination and arrangement of parts hereinafter described and set forth in the claims.

45 In the accompanying drawings, wherein a convenient embodiment of my invention is set forth,

Fig. 1 is an end elevation, parts in section, of a loom having my invention applied thereto, and 50 shown in stopped position at the beginning of a normal shuttle changing period.

55 Figs. 2 and 3 are views on an enlarged scale of a portion of Fig. 1 showing the parts in different positions,

Fig. 4 is a vertical section on an enlarged scale taken on line 4—4, Fig. 1.

Fig. 5 is a detailed horizontal section on line 5—5, Fig. 4.

Fig. 6 is a detailed horizontal position on line 6—6 of Fig. 2.

Fig. 7 is a schematic view showing the operating relations of certain parts shown in Fig. 1.

Fig. 8 is a plan view partly in section taken in 10 the direction of arrow 8, Fig. 7.

Fig. 9 is a vertical section on line 9—9 of Fig. 7.

Fig. 10 is a detail front elevation looking in the direction of arrow 10, Fig. 1, on an enlarged scale,

Fig. 11 is a side elevation looking in the direction of arrow 11, Fig. 10.

Fig. 12 is a vertical section on line 12—12, Fig. 10.

Fig. 13 is a fragmentary side elevation on an enlarged scale of the hook control shown in Fig. 20 1, and

Fig. 14 is a horizontal section on line 14—14, Fig. 13.

Referring particularly to Fig. 1, the loom frame 10 supports a lay 11 with upper and lower shuttle boxes 12 and 13, respectively, having binders 14 which cooperate with protector fingers 15. Upper and lower shuttles S and S' are preferably picked together into and out of the shuttle boxes and the protector fingers move with daggers 16 in the usual manner with protector rods 17 so that as the lay moves around its axis 18 these daggers will operate to stop the loom if one or the other of the shuttle boxes is unoccupied as the lay approaches its forward position, which is to the left of that shown in Fig. 1.

Front and back reserve shuttle magazines 21 and 22, respectively are held in fixed position on a bracket 20 fixed to the loom frame. Transfer heads or conveyors 25 and 26 for the front and back magazines, respectively, are each provided with a shuttle supporting shelf 27 to receive a reserve shuttle from the corresponding magazine. Front and back conveyor levers 30 and 31, respectively, pivot about a stud 32 and are normally urged to move rearwardly or to the right, Fig. 1, toward the lay by heavy tension springs 33 anchored at their lower ends to fixed structure. The front conveyor is connected to an operating rod 35 the forward end of which is attached to a conveyor operating lever 36 pivoted as at 34 and having operative relation with a cam 37 secured to and rotatable with a change shaft 38. The latter is normally at rest but rotates during the shuttle changing period. The rear conveyor lever 31 is connected by an operating rod 39 to a second conveyor operating lever 40 likewise pivoted at 34 and coacting with a cam 41 also secured to the change shaft 38.

When the shuttle changing mechanism is at 60 rest the cams are approximately in the position shown in Fig. 1, but as the shaft 38 rotates in the direction of arrow A, Fig. 1, the conveyor levers are first given a slight forward motion to the left as viewed in Fig. 1 by cam risers a and are maintained in this position by dwells 45, after which continued rotation of the shaft presents declining cam areas 46 to the levers 36 and 40 to permit the springs 33 to move the conveyors rearwardly toward the lay to place reserve shuttles in the 65 shuttle boxes. Continued rotation of shaft 38 acts to return the conveyors to their forward positions by rises b. These motions occur during a normal shuttle change and the springs 33 supply the forces which actually move the conveyors 70 rearwardly.

Prior to movement of the conveyors toward the lay a box front 47 on the lay is elevated to permit ejection of the depleted active shuttles from the boxes 12 and 13. When the box front rises and the depleted shuttles move forwardly the protector fingers will move in or to their stopping position, this action taking place before the conveyors have had any considerable rearward motion. The operating connections for moving the box front 47 are not set forth herein but may if desired be 10 as set forth in patent to Cowan No. 1,906,544.

Figs. 7, 8 and 9 show the mechanism for controlling the stopping of the loom. A solenoid 50 is normally deenergized so that a dog 51 lies below the path of a knock-off lever 52 regularly reciprocated by a cam 53 on a shaft 54 of the loom driven as indicated in Fig. 7. So long as both shuttles have sufficient weft the solenoid is deenergized, but when the detector mechanism not shown calls for a change because of weft exhaustion in either 20 shuttle the solenoid is energized by connections not shown to raise the dog into the path of lever 52, whereupon rod 55 is given a longitudinal movement to the left as viewed in Fig. 9 to rock two arms 42 and 43 secured to a short shaft 44 in bearing 48, see Figs. 7 and 9. Rod 63 is pivoted to arm 43, and when moved forwardly, to the left in Fig. 7, rocks a bell crank lever 60 in a clockwise direction about a fixed axis 61 against the action of spring 64.

An arm 65 of lever 60 has a lip 66 lying under an arm 67 pivoting about fixed axis 61 and connected to a rod 68 extending upwardly and attached to a rock shaft 69 mounted in bearings 70. A finger 71 secured to shaft 69 carries a depending rod 72 connected to a similar finger 73 on a shipper shaft 74. The latter rocks in bearings one of which is shown at 75, and extends rearwardly to shipper mechanism not shown but operative to stop the loom when the shaft 44 is rocked by down motion of rod 72. Forward motion of rod 63 acts through lip 66, arm 67 and rod 68 to give the necessary down motion to rod 72. Cam 53 is set on shaft 54 so as to cause the stopping impulse to lever 60 just after the 45 shuttles are picked from the side of the loom opposite the magazines, the loom coming to rest with the lay in rear position, as is common in shuttle changing looms of this type.

Pivoted to arm 65 is a depending rod 56 pivoted at its lower end to one end of a lever 23 to the other end of which is attached an upright rod 24. Lever 23 is pivoted between its ends so that up motion of rod 56 causes down motion of rod 24, and the latter is connected to an 55 arm 57 which moves a finger 58 to connect a regularly moving disk 59 to a clutch disk 28 fast on change shaft 38. The particular form of clutch for shaft 38 forms no part of my invention and it is sufficient for present purposes to 60 state that the normally stationary change shaft is started on a complete slow rotation whenever rod 63 acts to lift rod 56. Thus it is that excitation of solenoid 50 causes loom stoppage, rotation of shaft 38, and end thrust of rod 63, the 65 latter being particularly useful in carrying out my invention.

It should be borne in mind that lever 52 must be given its full swing with cam 53 in the dotted position of Fig. 9 before the shipper is thrown to 70 stopping position, and that a slight inevitable runover of the loom will carry the cam to the dot and dash position of that figure, thereby permitting spring 64 to return rod 63 to its normal position to the right, as in Fig. 7, as the loom 75

stops. Arm 65 can drop without return rotation of shaft 74, and once shaft 38 starts to rotate it is independent of rods 56 and 63, and will continue its rotation throughout the shuttle changing period.

Part of the mechanism thus far described of itself forms no part of my present invention and it is sufficient to state that indication of weft exhaustion by the detector mechanism on that side 10 of the loom opposite the conveyors will result in operation of solenoid 50 and rod 63. For further reference as to the structure and operation of the solenoid reference may be had to Payne Patent No. 1,873,465, while the change shaft clutch may 15 be seen in greater detail in the aforesaid Cowan patent.

The controller to prevent a shuttle change is shown in Figs. 1, 7, 13 and 14. A fixed stand 80 on the support 20 has pivoted thereto as at 81 an arm 82 the upper end of which is connected to a forwardly extending restarting controller rod 83. At an intermediate part of arm 82 there is pivoted as at 79 a hook 84 which moves with an 20 upstanding short finger 85. This finger is pivotally connected to the forward end of a rod 86 which has two threaded forks 87 and 88, respectively, see Fig. 6.

A stand 90, see Figs. 1, 2 and 3, is secured to the loom frame and carries a pivot stud 91 on which 30 are pivotally mounted two hook controlling arms 92 and 93, respectively, slotted to fit around forks 87 and 88, respectively. Arm 92 carries a resetting finger 94 which projects forwardly, while a similar finger 95 is movable with arm 93. A setting cam arm 96 is rigid with arm 92, while a second setting cam arm 97 moves with arm 93. These cam arms project rearwardly and are arranged for cooperation with a cam block 98 fixed 35 to but adjustable longitudinally along rod 63.

The resetting fingers 94 and 95 are bent upwardly as at 99 to cooperate with lugs 100 carried by lifter arms 101 and 102 movable, respectively, with the protector fingers for the upper and lower shuttle boxes, see Figs. 4 and 5. The arms 101 40 and 102 move back and forth with the lay and relatively to the fingers 94 and 95. Each of the arms 92 and 93 has attached thereto a flexible friction arm 105 movable between friction springs 106 carried by stand 90 to hold said arms yieldingly in any position to which they may be moved by block 98 or lugs 100. A light spring 107 connected to the top of finger 85 counterbalances the weight of the hook and acts to move the rod 86 forwardly, or to the left in Fig. 1, but is not 45 strong enough to disturb the friction devices just described. An adjustable screw 76 on arm 82 is engaged by finger 85 when the latter moves to the left, Fig. 13, so that spring 107 acts not only to lift hook 84 but also holds it yieldingly in forward 50 position.

As long as the shuttles are boxed at the detector end the lifter arms 101 and 102 will be raised and would therefore interfere with the down motion of the resetting fingers 94 and 95 induced by the cam block 98. To prevent this 55 interference the lugs 100 do not reach the resetting fingers as the lay moves rearwardly until after picking, hence the lugs have time to move down before they can engage the resetting fingers 70 and the latter can retain a low setting. Loom stoppage for shuttle change can therefore be initiated early in the backward stroke of the lay.

In operation, the normal position of the parts 75 would be with the hook 84 raised and the arms 92 and 93 in left hand position as shown in Fig. 1.

with the setting arms 96 and 97 down and the block or member 98 in rear position or to the right as viewed in Fig. 1. When rod 63 moves forwardly at the beginning of the shuttle changing period the block 98 will be carried from the full to the dotted line position shown in Fig. 7 5 and cause inclined surface 108 of the block to raise the setting arms and rock arms 92 and 93 to the left, Fig. 2, to cause lowering of the resetting arms 94 and 95. Arms 92 and 93 also move rod 86 rearwardly and lower the hook 84 into alignment with lugs 78 on the conveyors. As already described the block 98 will then move back from the full to the dotted line position shown in Fig. 2 because of movement of cam 53 beyond the 10 knock-off lever 52, but the friction springs 105 will hold the resetting fingers elevated. Hook 84, which was moved down when arms 92 and 93 moved to the right, Fig. 2, remains in this position aligned with lugs 78 on the conveyor levers. 15

A short time thereafter, assuming that both shuttles arrive at the magazine side correctly, the lugs 100 will be raised to lift the resetting fingers 94 and 95, moving the arms 92 and 93 forwardly, 20 to the left in Fig. 1, and permitting spring 107 to rock arm 86 in a left hand direction to lift the hook 84 above the lugs 78. The conveyor levers may therefore under these conditions have 25 their normal rearward motion to place reserve 30 shuttles in the boxes 12 and 13.

If one of the shuttles should fail to be boxed, such as the upper one, a condition set forth in Fig. 3 will result and lifter 101 will remain down, 35 permitting the control arm 92 to remain to the right and hold rod 86 rearwardly, thereby retaining the hook 84 in down position against the action of light spring 107. As the conveyor levers attempt to move rearwardly their lugs 78 will engage the hook and shuttle change will be prevented. The conveyor levers will continue to move rearwardly a short distance, moving the hook 84 back and carrying the rod 83 also rearwardly. 40

In order to restart the loom after shuttle 45 change and prevent restarting if the shuttle change has been prevented, I provide the mechanism shown particularly in Figs. 1, 10, 11 and 12. The change shaft has secured thereto a restarting cam 110 to rock a restarting lever 111 on fixed pivot 112 and having an upstanding arm 113 to which is attached a tension spring 114. The latter is connected to the bottom of a vertical slide bar 115 having a slot 116 to receive a pin 117 on lever 111. The slot and spring provide a giveaway connection between cam 110 and the bar. 50

The upper end of the bar has a shoulder 118, 55 see Fig. 12, lying under a web 119 of a yoke 120 through which the upper end 121 of the bar passes. The yoke guides the bar and is of sufficient width to permit the bar to move far enough to the right from the position shown in full lines, Fig. 12, to permit the shoulder to move out of vertical alignment with the web 119. The yoke 60 has a hub 122 fastened to restarting shaft 74. Near the end of the shuttle changing period the cam 110 will rock lever 111 in a clockwise direction, Fig. 1, and if the transfer has been normal with rod 83 forward, spring 114 will raise the bar 65 to effect rocking of shaft 74 by the shoulder and web, thus causing the loom to resume running. 70

Should shuttle change be interrupted as already 75 described, I provide means to prevent restarting. The rod 83 has its forward end slotted at 131 to 75

receive the reduced top end 121 of the restarting bar, see Fig. 11. Spring 114 normally holds the shoulder under the web, but when the conveyors start the first part of their rearward motion they move the hook rearwardly a slight amount, as already described, to cause backward motion of arm 82, thereby moving the rod 83 and the top of the bar 115 rearwardly to place shoulder 118 out of vertical alignment with web 119, as shown in dotted lines in Fig. 12.

In the latter part of the shuttle changing period the conveyor levers will move forwardly to move the lugs 78 away from the hook but the gradual rise on cam 110 will have lifted shoulder 118 slightly above web 119 before the hook starts to return forwardly to its normal front position. Movement of lugs 78 will therefore not cause loss of the setting of rod 83 and bar 115.

Operation of lever 111 by cam 110 at the end of the shuttle changing period will therefore result in an idle upward motion of bar 115 and the shipper shaft 74 will remain at rest to prevent loom restarting. During the first part of the shuttle changing period, when upper end 121 of the bar moves to the right under action of the hook, said end engages the right part of the yoke 120 as in dotted lines, Fig. 12, and further rearward motion of rod 83 is prevented, hook 84 being thus held to prevent further rear motion of the conveyors.

From the foregoing it will be seen that I have provided means which move at the beginning of the shuttle changing period to a position to prevent shuttle change and in addition have provided mechanism to be operated by the arrival of both shuttles to move the restraining element back to normal non-restraining position. If either shuttle fails to be boxed, however, the restraining element will remain in position to prevent the conveyor levers from moving toward the lay. These controls are exercised through the protector fingers as soon as the shuttles are boxed and therefore before the ejection of the active shuttle can interfere with the control mechanism. Furthermore, since the restraining hook is moved out of holding position upon the arrival of both shuttles at the magazine side of the loom it is immaterial what time relation exists between the ejection of the depleted shuttles and the movement of the conveyors and the latter can start their backward movement while the lugs 78 are still in front of the hook 84 after the depleted shuttles have been ejected from the shuttle boxes and the protector fingers have moved to stopping position. It will be seen that this latter movement of the protector fingers does not in any way affect the setting of the hook. Furthermore, when shuttle change is prevented means are provided to prevent the loom from restarting, preferably by the hook which restrains the conveyor lever.

The term "shuttle changing period" used in the foregoing description refers to that period in loom operation in which the depleted shuttle is discharged and the reserve shuttle is placed on the lay. This period may begin as soon as the lay comes to rest in the rear position and last until the restarting mechanism resumes loom operation, although I do not wish to be limited to a loom which necessarily stops for shuttle replacement.

While I have shown herein mechanism to prevent restarting of the loom should the active shuttles fail to be boxed at the beginning of the shuttle changing period, yet the same is not

claimed herein since such features are described and claimed in my co-pending application Serial No. 34,661 filed Aug. 5, 1935.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a shuttle box from which a depleted shuttle is removed during the shuttle changing period, protector mechanism to be positioned by a shuttle in the shuttle box, stopping means to stop the loom during the shuttle changing period, shuttle changing mechanism effective to place a reserve shuttle into the shuttle box, preventing mechanism to arrest operation of the shuttle changing mechanism, control means for the preventing mechanism, actuated by the stopping means to move the preventing mechanism into arresting relation with respect to the shuttle changing mechanism, the protector mechanism thereafter operative when the shuttle box is occupied by a depleted shuttle to actuate the control means and thereby cause the latter to move the preventing mechanism out of arresting relation with respect to the shuttle changing mechanism.

2. In a shuttle changing loom which is at rest during the shuttle changing period, a shuttle box on the lay, shuttle changing mechanism to place a reserve shuttle into the shuttle box during the shuttle changing period, preventer means capable of arresting operation of the shuttle changing mechanism, loom stopping means, protector means, and control connections between the preventing means and the stopping and protector means effective by a control exerted by the stopping means to move the preventer means into arresting relation relatively to the shuttle changing mechanism and thereafter effective by a control exerted by the protector means to move the preventer means out of arresting relation relatively to the shuttle changing mechanism if a shuttle is in the shuttle box at the beginning of the shuttle changing period.

3. In a shuttle changing loom operating with a shuttle box from which a depleted shuttle is removed during the shuttle changing period, a reserve shuttle conveyor, a preventer for the shuttle conveyor normally out of arresting relation with respect to the shuttle conveyor, means operative prior to removal of the depleted shuttle from the shuttle box to move the preventer into position to arrest operation of the shuttle conveyor, and means operated by arrival of the depleted shuttle in the shuttle box to move the preventer out of arresting relation with respect to the shuttle conveyor.

4. In a shuttle changing loom having a lay and a shuttle box, protector mechanism, stopping means to cause the loom to be at rest during a shuttle changing period, shuttle changing mechanism, a conveyor forming part of the shuttle changing mechanism, preventing mechanism to arrest operation of the conveyor, and a controller for the preventing mechanism movable by the stopping mechanism when the latter arrests loom operation to set the preventer mechanism to prevent operation of the conveyor, said controller also operatively related to the protector mechanism to be moved by the latter to render the preventing mechanism capable of moving out of restraining relation with respect to the conveyor when the shuttle box is occupied by a shuttle.

5. In a shuttle changing loom having a lay and shuttle box from which a depleted shuttle is removed at the beginning of a shuttle changing period, stopping mechanism to cause the loom 5 to be at rest during the shuttle changing period, a reserve shuttle conveyor, preventing means to arrest operation of the conveyor and normally out of arresting position with respect to the conveyor, a controller to connect the stopping mechanism and the preventing mechanism to move the latter into restraining relation with respect to the conveyor, and protector mechanism effective by presence of a depleted shuttle in the shuttle box to move the controller in a direction 10 to render the preventing mechanism capable of moving out of restraining relation with respect to the conveyor.
6. In a shuttle changing loom having a shuttle box from which a depleted shuttle is removed 20 during the first part of a shuttle changing period, shuttle changing mechanism, a conveyor forming part of the shuttle changing mechanism to move a reserve shuttle from the shuttle box, preventing mechanism to the shuttle box, preventing mechanism capable of arresting operation of the conveyor, stopping means to cause the loom 25 to be at rest during the shuttle changing period, protector mechanism to detect the presence of a depleted shuttle in the shuttle box, and operative connections between the preventing mechanism 30 and the stopping means and protector mechanism effective first to move the preventing mechanism into position to arrest operation of the conveyor by a force derived from the stopping means and thereafter effective by a control exercised by the 35 protector mechanism to effect movement of the preventing means out of restraining position with respect to the conveyor when the protector mechanism detects presence of a depleted shuttle in the shuttle box.
7. In a shuttle changing loom which effects a shuttle changing operation in a given period, a shuttle advancer normally operating at an intermediate point between the beginning and ending of the period, preventing means to interrupt motion of the advancer, means operative prior to said intermediate point to move the preventing means into arresting relation with respect to the shuttle advancing means to prevent completion 40 of the normal movement of said reserve shuttle moving means, and mechanism operated by the depleted active shuttle when arriving at the end of the loom adjacent the reserve shuttle advancing means and subsequent to operation of the preventing means but prior to said intermediate point to move the preventing means out of preventing relation with respect to the reserve shuttle advancing means.
8. In a shuttle changing loom which is at rest during the shuttle changing period, a shuttle changer, preventing means therefor, a setting element, means operative when the loom comes to rest at the beginning of the shuttle changing 5 period to move into relation with respect to the setting element to move the latter from normal to abnormal position and then move out of operative relation with respect to the setting element, protector mechanism to move the setting 10 element back to normal position when the active depleted shuttle arrives at the shuttle changer side of the loom, operative connections between the setting element and preventer means effective to move the preventing means into 15 arresting relation with respect to the shuttle changer when the setting element is in abnormal position, and means to move the preventing means out of arresting relation with respect to the shuttle 20 changer when the setting element is returned to normal position by the protector mechanism.
9. In a shuttle changing loom which is at rest during the shuttle changing period, a shuttle changer, preventing means normally out of holding 25 relation with respect to the changer, stopping means for the loom, a setting element normally in running position, connections between the setting element and the preventing means, a member movable by the stopping means to give 30 the setting element a movement to position the preventing means in restraining relation with respect to the shuttle changer, and means operative thereafter by the depleted shuttle when arriving at the shuttle changer side of the loom 35 to return the setting element to running position, whereupon the preventing means moves out of restraining relation with respect to the shuttle changer.
10. In a shuttle changing loom having a shuttle 40 box from which a depleted shuttle is removed during the shuttle changing period, a protector finger movable to running position when the depleted shuttle is in the shuttle box and movable to stopping position when the depleted shuttle 45 has been removed from the shuttle box, a shuttle changer, a preventer to arrest operation of the shuttle changer, a controller for the preventer movable to shuttle changing position by the protector finger when the latter moves to running 50 position, means to move the preventer out of arresting position as long as the controller is in shuttle changing position, and means additional to the protector finger to hold the controller in shuttle changing position after the protector 55 finger moves to stopping position due to removal of the depleted shuttle from the shuttle box.

WILLIAM W. ROBERTSON.
